UNITED STATES PATENT OFFICE.

ABRAM E. MACK, OF NEW HAVEN, CONNECTICUT.

DESIGN FOR A CHECK-BIT.

SPECIFICATION forming part of Design No. 26,281, dated November 17, 1896.

Application filed September 28, 1896. Serial No. 607,262. Term of patent 3¹ years.

To all whom it may concern:

Be it known that I, ABRAM E. MACK, of New Haven, in the county of New Haven and State of Connecticut, have invented a new Design 5 for a Check-Bit; and I do hereby declare the following, when taken in connection with the accompanying drawing and the letters of reference marked thereon, to be a full, clear, and exact description of the same, and which said 10 drawing constitutes part of this specification and represents a perspective view of a check-bit embodying my design.

This invention relates to a design for a 15 check-bit; and the design consists in the configuration, as shown in the accompanying illustration and hereinafter described.

As herein shown, the design consists of a

bowed mouthpiece A, terminating in upwardly-extending arms B B and downwardly-extending arms C C, which are each provided 20 with eyes D D, standing in a plane at right angles to the plane of the bit, the arms B appearing as a continuation of the mouthpiece A.

I claim--

25

The design for a check-bit as herein shown and described.

In testimony whereof I have signed this specification in the presence of two subscribing witnesses.

ABRAM E. MACK.
